Specification for Design.

Patented Apr. 22, 1913.

Application filed February 20, 1913. Serial No. 749,733. Term of patent 7 years.

To all whom it may concern:

Be it known that I, HARRY H. HUNT, a citizen of the United States, residing at Jenkintown, Montgomery county, State of Pennsylvania, have invented a certain new, original, and ornamental Design for a Rug, of which the following is a specification, reference being had to the accompanying drawing, forming part thereof.

The figure is a plan view of a half section

of a woven cotton bath rug, the other half section being identical therewith, showing my new design.

I claim:

The ornamental design for a rug, as shown.

HARRY H. HUNT.
